UNITED STATES PATENT OFFICE.

FREDRIC M. PARKER, OF WORCESTER, MASSACHUSETTS, ASSIGNOR TO
WILLIAM JAMES HOGG, OF SAME PLACE.

DESIGN FOR CARPET.

SPECIFICATION forming part of Design No. 24,359, dated June 4, 1895.

Application filed February 20, 1895. Serial No. 539,320. Term of patent 3½ years.

To all whom it may concern:

Be it known that I, FREDRIC M. PARKER, a citizen of the United States, residing at Worcester, in the county of Worcester and 5 State of Massachusetts, have invented and produced a new and useful Design for Carpeting, of which the following is a specification.

My invention relates to a design to be 10 worked into or upon surfaces, such as carpeting or similar fabrics, and it consists of the novel features illustrated in the drawing forming a part of this specification.

The accompanying drawing is a face view 15 of a carpet embodying my new design. The drawing illustrates a body and a border.

The body A consists of a back-ground or ground-work, having conventionalized figures appearing thereon. The back-ground or 20 ground-work is substantially uniform, and embodies wavy or curved lines, which are offset or staggered with respect to each other. The detached, conventionalized figures are of two forms, a smaller figure being alternately 25 placed between the larger figures.

The border B consists of a ground-work of

the same character as before described, the ground-work having detached, conventionalized figures appearing thereon, which conform to the figures employed in the body. 30 The ground-work of the border is shaded off into a darker margin at the edge.

The colors which may be employed in my new design may be varied to suit the taste or convenience of the manufacturer. 35

What I claim as new, and desire to secure by Letters Patent of the United States, is—

1. In a design for carpeting, the body A, substantially as shown.

2. In a design for carpeting, the border B, 40 substantially as shown.

3. The design for a carpet, consisting of the body A and the border B, substantially as shown.

In testimony whereof I have hereunto set 45 my hand in the presence of two subscribing witnesses.

FREDRIC M. PARKER.
